UNITED STATES PATENT OFFICE.

ALBERT B. DICK, OF LAKE FOREST, ILLINOIS, ASSIGNOR TO A. B. DICK COMPANY, OF CHICAGO, ILLINOIS, A CORPORATION OF ILLINOIS.

STENCILING MATERIAL.

1,223,773.

Specification of Letters Patent. Patented Apr. 24, 1917.

Application filed December 15, 1916. Serial No. 137,129.

To all whom it may concern:

Be it known that I, ALBERT B. DICK, a citizen of the United States, residing at Lake Forest, in the county of Lake and State of Illinois, have invented certain new and useful Improvements in Stenciling Material, of which the following is a specification.

My invention relates to stencil-sheets and their backing, and particularly to the use of 10 stencil-sheets which for their efficient operation require moistening as a preliminary to the striking of the type thereon. Such stencil sheets are commonly made of open porous material, such as Yoshino paper, impregnated with a colloidal substance, such as coagulated protein containing a suitable tempering ingredient. Such stencil-sheets have been combined, as in my Patent No. 1,101,259, dated June 23, 1914, for stenciling 15 material, with a carrier-sheet of hard firm paper, and an interposed sheet (termed in said patent a backing-sheet) of soft, absorbent paper or other suitable material, adapted to take up a moistening fluid such 20 as water, glycerin and Turkey red oil.

As is described in the said patent, the carrier-sheet of stiff firm paper is coated with varnish, and the absorbent backing-sheet is secured thereto throughout substantially its 25 whole expanse. The backing-sheet is sufficiently absorptive to take up the moistening fluid for the purpose of moistening the stencil-sheet overlying the same. My present invention constitutes an improvement 30 over such an arrangement, which enables superior results to be attained in several respects.

My improvement involves interposing a thin coating of waxlike material, such, for 35 example, as hard paraffin or the like, between the upper surface of the carrier-sheet and the backing-sheet, and this is preferably done by coating one side of the latter with the paraffin, and then affixing the backing- 40 sheet to the carrier-sheet with the wax surface next to the upper surface thereof, which may, if desired, have previously been provided with a coating of varnish. This has the effect of making the under side of 45 the backing-sheet more resistant to moisture than it otherwise would be, while at the same time the combined sheets are desirably flexible. The use of the paraffin prevents 50 leakage of moisture into the body of the carrier-sheet, which would cause the latter to

become soft, and render it a poor resistant for the type in making a stencil in the typewriter.

In addition to the above, my new procedure enables me to make clear stencils with 55 less effort than has heretofore been possible. This may be due to the character of the resistance to the impact of the type offered by the combination of the waxlike material and the firm, hard carrier-sheet. Or it may be 60 that since the former prevents the moistening solution from passing through the backing, the stencil-sheet is maintained in more nearly ideal condition for typing. However this may be, I have demonstrated the 65 fact by comparative tests with various makes of typewriters, with all of which the application of the same force on the typewriter key produces a clearer stencil with the stenciling material described herein than with 70 that in which the described waxy coating is not used.

My invention comprises the stenciling material and also the method of preparing the 75 same as described above.

In order that a clearer understanding of my invention may be had, attention is hereby directed to the accompanying drawings forming part of this application and illustrating an embodiment thereof. In the 80 drawings, Figure 1 represents a front elevation of a combined stencil-sheet, backing-sheet and carrier-sheet and Fig. 2 is an enlarged cross-section through the same shown broken away.

Referring to the drawings, A represents the stencil-sheet, B the backing-sheet, preferably of absorbent paper or other suitable material, and C the carrier-sheet. The latter is preferably made of fairly stiff firm 85 paper having a varnished surface, as is shown at d in Fig. 2. This varnish coating is such as leaves the carrier-sheet sufficiently pliable to be easily handled in the typewriter. It is, to a considerable extent, impervious to moisture and may also, if desired, act as an adhesive for the purpose of binding thereto the layer of paraffin on the 90 backing-sheet B, when, as is preferable, the backing-sheet and paraffin are permanently 100 secured to the carrier-sheet. The coating of paraffin on the under side of backing-sheet B is shown at e in the drawings. This paraffin or similar waxy material is coated 105 on the backing-sheet B in a thin layer, and 110

the backing-sheet is then laid on the carrier-sheet C, preferably before the varnish d on the surface of the latter has dried, the layer of paraffin e being next to the varnish surface. The combination of sheets is then, in my preferred process, subjected to pressure during which the process of drying out may continue. As a result, the backing-sheet is firmly, evenly and permanently combined 10 with the carrier-sheet. The stencil-sheet A may then be secured in the usual manner at one end to the carrier-sheet, so as to overlie the backing-sheet.

The combination is used in the same manner as formerly, that is to say, when the stencil is to be typed in a typewriter, or the like, the stencil-sheet is laid back, the moistening compound applied to the backing-sheet and the stencil-sheet replaced, after which the combination may be introduced 20 into the writing-machine for the stencil-cutting operation.

Having now described my invention, what I claim as new therein and desire to secure 25 by Letters Patent is as follows:—

1. In stenciling material, the combination with a stencil-sheet, of a firm but flexible carrier-sheet and a backing-sheet between said stencil-sheet and carrier-sheet, said 30 backing-sheet having a thin coating of waxy-like material, impervious to moisture, on the side thereof adjacent to the coacting surface of said carrier-sheet, substantially as set forth.

35 2. In stenciling material, the combination with a stencil-sheet, of a firm but flexible carrier-sheet and an absorbent backing-sheet between said stencil-sheet and carrier-sheet, said backing-sheet having a thin coating 40 of waxy-like material, impervious to moisture, on the side thereof adjacent to the coacting surface of said carrier-sheet, substantially as set forth.

3. In stenciling material, the combination 45 with a stencil-sheet, of a firm but flexible carrier-sheet and an absorbent backing-sheet

between said stencil-sheet and carrier-sheet, said backing-sheet having a thin coating of hard waxlike material, impervious to moisture, on the side thereof adjacent the coacting surface of said carrier-sheet, substantially as set forth.

4. In stenciling material, the combination with a stencil-sheet, of a firm but flexible varnished carrier-sheet and an absorbent 55 backing-sheet between said stencil-sheet and carrier-sheet, said backing-sheet having a thin coating of waxlike material, impervious to moisture, on the side thereof adjacent the coacting varnished surface of said carrier-sheet, substantially as set forth.

5. In stenciling material, a backing for a stencil-sheet comprising a firm but flexible varnished carrier-sheet and an absorbent 65 backing-sheet thereon with a thin layer of hard waxy material between the varnished surface of said carrier-sheet and the body of said absorbent backing-sheet, said backing-sheet, waxy material and carrier-sheet being secured together throughout substantially 70 the entire expanse of said backing-sheet, and said waxy material and the varnish coating on said carrier-sheet being together impervious to moisture contained in said absorbent backing-sheet, substantially 75 as set forth.

6. The method of preparing stenciling material, comprising coating an absorbent backing-sheet on one side with a thin layer of hard waxy material, affixing the same 80 to a firm varnished carrier-sheet with the layer of waxy material next to the varnished surface of the carrier-sheet, and securing a stencil-sheet at one end to the backing thus formed, so that the same will overlie said 85 backing-sheet, substantially as set forth.

This specification signed and witnessed this 8th day of December, 1916.

ALBERT B. DICK.
